JALOUSIE

Tomlinson I. Moseley, Atherton, Calif.

Application August 24, 1948, Serial No. 45,829

7 Claims. (Cl. 20—62)

1

This invention relates to a jalousie, more particularly, to an improved form of crank-operated jalousie.

It is an object of the present invention to provide a jalousie of the crank-operated type wherein several of the mechanical elements employed to operate the slats of the jalousie are concealed from view.

It is a further object of the invention to provide an improved form of jalousie which provides effective weather stripping without unsightliness.

It is a still further object of the invention to provide a jalousie wherein the slats form a tight closure without a marked tendency to bind, or to develop cracks on shrinking.

These and other objects of the invention will be apparent from the ensuing description and the appended claims.

One form which the invention may assume is exemplified in the following description and illustrated by way of example in the accompanying drawings, in which:

Fig. 1 is a longitudinal mid-section through the jalousie of the invention.

Fig. 2 is a section taken along the line 2—2 of Fig. 1.

Fig. 3 is a fragmentary, perspective view of the slats of the jalousie as seen from their exterior.

Fig. 4 is a section taken along the line 4—4 of Fig. 1, partly broken away and with the slats removed, showing the means of mounting and concealing the mechanical elements employed to operate the slats and also showing details of the weather stripping.

Figs. 5 and 6 are sections taken along the lines 5—5 and 6—6, respectively, of Fig. 4, showing details of the mechanical elements employed to operate the slats.

Referring now to the drawings, a window frame 1 is provided comprising the usual sill 2, head rail 3 and jambs 4 which, however, are modified as described hereinafter. A plurality of slats 10 are provided, including a stationary slat 11 at the top and any desired number of pivotal slats 12 therebelow. The stationary slat 11 is secured to the rail 3 by any suitable means, as by a mortise and tenon joint at 13 and nails 14, and a sealing member or staff mold 15 is also provided to provide a seal between the rail and the wall 16.

The pivotal slats 12 are supported by means of levers 17 (a pair of which are secured to opposite sides of each slat 12), pivot bars 18 (one such bar being secured to each jamb) and pivot pins 19 extending through each lever 17 and its adjacent pivot bar 18. Each lever 17 is generally of

2

right angular cross section, and it is provided with an upwardly and inwardly extending arm 25 and, outwardly of the slats 12, with a flange 26 of curvilinear transverse cross section having an enlargement or boss 27 at its lower end. The levers 17 are secured to the slats 12 by means of screws 28, and the pivot bars 18 are secured to the jambs by means of screws 29. It will also be noted that the pivot bars 18 extend outwardly of the slats 12 and jambs 4, and that the position of the levers 17 and the curvature of the flanges 26 are such that the latter abut the pivot bars when the slats are in closed position, thus providing a seal or weather stripping. Also, each boss 27 overlaps the next lower flange 27, thus providing a continuous seal the length of the window.

Each of the slats 11, 12 is recessed or rabbeted at its lower end to provide a tongue 30 and a recess 31, and at its upper end each pivotal slat 12 is somewhat similarly rabbeted, except that the recess 31a is sloped upwardly, as shown, and extends inwardly of the tongue 30a to provide a groove 32. The sill 2 is similarly rabbeted to provide a groove 33 and tongue 34.

It will thus be seen that each of the pivotal slats 12 can be pivoted outwardly to open position and inwardly to closed position, and that in the latter position the flanges 26 provide a weather stripping which is effective and of pleasing appearance. It is also apparent that, when the slats are in closed position, the rabbeted joints provide an effective closure and combine therewith a pleasing appearance. Also, the rabbeted joints are such as not to bind and as always to provide a tight closure even when the wood shrinks.

To operate the slats 12, there is provided a mechanism which will now be described. The usual travel bars 40 are provided, one at each side of the window, and the arms 25 of the levers 17 are pivotally connected to the travel bars 40 as at 41. The lower end of each travel bar 40 is pivotally connected at 42 to a link 43, the other end of which is pivotally secured at 44 to a crank arm 45. Each crank arm 45 is secured to an operating shaft 46. At one end the operating shaft is received within a recess 47 formed in the jamb 4 and is journalled in a bearing plate 48 secured to the adjacent jamb by means of screws 49. The other end of the operating shaft is journalled in a bearing plate 50 secured to the jamb by means of screws 55 and is received within a relatively large recess 56 formed in the jamb, for which the bearing plate 50 serves as a closure.

A worm wheel section 57 is secured to the operating shaft 46 within the recess 56, and an operating crank 58 journalled in the bearing plate 50 and in a bearing block 59 secured to the plate 50 is provided with a worm 60 integral therewith and in mesh with the worm wheel sector 57. A stop pin 61 is also provided to limit angular movement of the worm wheel sector 57 and, hence, of the pivotal slats 12.

Crank means, including meshing gears, is thus provided for opening and closing the pivotal slats 12, which means is compactly arranged within one of the jambs of the window frame and is thus concealed from view.

It will thus be seen that a jalousie or Venetian blind structure is provided which affords several advantageous features. Thus, an effective, continuous weather stripping is provided, which is of pleasing appearance. An effective form of joint between slats is provided, which does not or is less likely to bind or develop cracks on swelling or shrinking. Manually operable crank means of simple and rugged construction are provided but are concealed from view.

While I have shown the preferred form of my invention, it is to be understood that various changes may be made in its construction by those skilled in the art without departing from the spirit of the invention as defined by the appended claims.

Having thus described my invention, what I claim and desire to secure by Letters Patent is:

1. A jalousie comprising a wooden framework including side members, a plurality of wooden slats, a metal pivot strip secured to and extending longitudinally of each side member and projecting outwardly of said side member, a metal sealing strip secured to each end of each slat, each sealing strip being of generally Z-section having an inner portion secured to a slat, a middle portion adjacent an end of such slat and opposite a pivot strip, and an outer portion of curvilinear section, and a pivotal connection between the upper end of each sealing strip and the adjacent pivot strip, said outer portion of curvilinear section being such as to abut the outer edge of said pivot strip when the slats are in closed position.

2. A jalousie comprising a wooden framework including side members, a plurality of wooden slats, a metal pivot strip secured to and extending longitudinally of each side member and projecting outwardly of said side member, a metal sealing strip secured to each end of each slat, each sealing strip being of generally Z-section having an inner portion secured to a slat, a middle portion adjacent an end of such slat and opposite a pivot strip, and an outer portion of curvilinear section, and a pivotal connection between the upper end of each sealing strip and the adjacent pivot strip, said outer portion of curvilinear section being such as to abut the outer edge of said pivot strip when the slats are in closed position and the lower portion of each sealing strip being enlarged and overlapping the upper portion of the next lower sealing strip.

3. A jalousie comprising a wooden framework, including opposed side members, a metal sealing member secured to and extending vertically of each side member, said metal sealing members occupying positions on the outer opposed corner of the side members, a plurality of wooden slats, a metal sealing strip secured to the end of each slat, each sealing strip being of generally Z sec-

tion having an inner portion secured to a slat, a middle portion adjacent one end of such slat, and an outer portion engageable with the adjacent sealing member when the slats are closed to form a seal, and a pivotal connection between the upper end of each sealing strip and the adjacent sealing member.

4. A jalousie comprising a wooden framework, including opposed side members, a metal sealing member secured to and extending vertically of each side member, said metal sealing members occupying positions on the outer opposed corner of the side members, a plurality of wooden slats, a metal sealing strip secured to the end of each slat, each sealing strip being of generally Z section having an inner portion secured to a slat, a middle portion adjacent one end of such slat, and an outer portion engageable with the adjacent sealing member when the slats are closed to form a seal, and a pivotal connection between each sealing strip at a point above the upper end of the outer portion thereof and the adjacent sealing member.

5. A jalousie comprising a wooden framework including opposed side members, a metal sealing member secured to and extending vertically of each side member, said metal sealing members occupying positions on the outer opposed corners of the side members, a plurality of wooden slats, a metal sealing strip secured to the end of each slat and having a laterally extending sealing portion engageable with the adjacent sealing member when the slats are closed to form a seal, and a pivotal connection between each sealing strip at a point above the upper end of the laterally extending portion thereof and the adjacent sealing member, each sealing strip having an offset extension formed at one end of its laterally extending portion arranged to overlap the adjacent sealing strip of the adjacent slat when the slats are in closed position to form a continuous seal from top to bottom of the series of slats.

6. A jalousie comprising a wooden framework including side members, a metal sealing member secured to and extending vertically of each side member, and projecting outwardly of said side member, a plurality of slats, a metal sealing strip secured to each end of each slat, each metal strip having a portion of curvilinear section engageable with the adjacent sealing member when the slats are closed to form a seal, a pivotal connection between each sealing strip at a point above the upper end of the curvilinear portion thereof and the adjacent sealing member, and each sealing strip having an offset extension formed at one end of each curvilinear section arranged to overlap the curvilinear section of the adjacent sealing strip when the slats are closed to form a continuous seal from top to bottom of the series of slats.

7. A jalousie comprising a framework, including opposed side members, a metal sealing member secured to and extending vertically of each side member, said metal sealing members occupying positions on the outer opposed corner of the side members, a plurality of slats, a metal sealing strip secured to the end of each slat, each sealing strip being of generally Z section having an inner portion secured to a slat, a middle portion adjacent one end of such slat, and an outer portion engageable with the adjacent sealing member when the slats are closed to form a seal, and a pivotal connection between

the upper end of each sealing strip and the adjacent sealing member.
